Theophilus Hessenbruch

THEOPHILUS HESSENBRUCH, OF PHILADELPHIA, PENNSYLVANIA.

Letters Patent No. 85,931, dated January 19, 1869.

STOVE-PIPE DAMPER.

The Schedule referred to in these Letters Patent and making part of the same.

To all whom it may concern:

Be it known that I, THEOPHILUS HESSENBRUCH, of the city of Philadelphia, in the State of Pennsylvania, have invented a new and useful Improvement in Dampers for Stove-Pipes; and I do hereby declare that the following is a full, clear, and exact description of the construction and operation of the same, reference being had to the accompanying drawings, making a part of this specification, in which—

Figure 1 is a vertical central section of the said damper and stove-pipe, and

Figures 2 and 3, plan views of the respective adjustable plates of the damper, as applied to the pipe.

Like letters of reference indicate the same parts when in the different figures.

The nature of my invention consists, substantially as hereinafter described, in the construction and arrangement of a pair of simultaneously-adjustable damper-plates, in such relation to each other, and to horizontal and vertical communicating portions of a stove-pipe, that whilst the draught from the fuel-chamber of the stove can be regulated at pleasure, and with facility, without causing any escape of gas into the room, the carbonic-acid gas, or heavy, foul air, which settles at the bottom of the said room, will be discharged up through the vertical portion of the pipe, and thus the air of the room be kept pure, as well as in a warm condition.

Referring to the drawings—

A is the horizontal portion of the stove-pipe, and a', its damper-plate;

B, the vertical portion of the pipe, and b', its damper-plate; and

C, an adjustable bottom on the lower open end of the vertical pipe B.

The portion A of the pipe forms an open communication between the stove (indicated by the faint lines *v-v* in fig. 1) and the vertical portion B, and has its damper-plate a' secured upon journals, so that it can be operated to nearly close and fully open, alternately, the said pipe, as occasion may require, the plate a' being notched out at a", so as to allow the fuel-gas to escape when the damper is closed, as seen in fig. 2.

The vertical portion B of the pipe extends downward from the intersection of the portion A, and opens at two or three inches above the floor of the room in which the stove may be located, and has its damper-plate b' fixed to a horizontal shaft, b", which projects through the side of B sufficiently to form a handle, b'', whereby the said plate b' can be readily caused to either open or close, partially or fully, the pipe B at a short distance below the intersection of A with B, as shown in fig. 1.

The two damper-plates a' and b' are connected together by means of a stiff bar of wire, b', the ends of which are articulated to the respective plates, so as to keep them in parallel planes, and cause any movement

which may be given to plate b' (by means of the handle b'') to be also given to plate a', as represented in the same figure.

The adjustable bottom C slips like a sleeve, in connection with the sides of the open lower end of B, so that when the said bottom, C, is pushed nearly its full length upward, (as indicated by the dotted lines,) it will close the said open end of B, and when slipped downward, as represented in the drawing, it will allow a free entrance of air, gas, or dust, through its capacious openings, c' c' c', into the vertical portion B of the pipe, and at the same time afford a cup for catching and retaining any soot or sparks that may fall from B.

It will be seen, when the damper-plates a' and b' are respectively in the positions shown in fig. 1, that, as the portion B of the stove-pipe is closed below the intersection of A therewith, (by the horizontal position of its damper-plate b',) and the portion A fully opened, (by the horizontal position of its damper-plate,) a full draught from the stove will be permitted, which is at times desirable, and especially so when the fire is being started; and it will also be seen, as the two damper-plates must move simultaneously in parallel planes, that when damper-plate b' is turned to a vertical position, the damper-plate a' will also be brought into a like position, and thus close A, (with the exception of the gas-vent a''), whilst B will be fully open from its lower end upward; and that if the adjustable bottom, C, be also open, as shown in fig. 1, the gas and foul air on the floor of the room will be carried up through B, and any soot or ashes that may fall from the latter will be caught and retained by C.

It will therefore be manifest that the draught from the fuel and that from the floor of the room, can be regulated together, to suit any requirements therefrom that may be desired in heating the room, and at the same time in preserving the purity of the air therein, with ready facility.

Although the bottom, C, can be used to close more effectually the lower end of B, if desired at any time, its principal function is to catch and retain any falling ashes, soot, or sparks of fire that may fall from B.

Having thus fully described my improvement, and shown its utility,

What I claim as new, of my invention, and desire to secure by Letters Patent, is confined to the following, viz:

The coupled damper-plates a' and b', in combination with the respective portions A and B of a stove-pipe, the same being constructed and arranged to operate together, substantially as and for the purpose described.

THEOPHILUS HESSENBRUCH.
